UNITED STATES PATENT OFFICE.

FRIEND W. SMITH, JR., OF BRIDGEPORT, CONNECTICUT, ASSIGNOR TO THE SMITH & EGGE MFG. CO., OF BRIDGEPORT, CONNECTICUT, A CORPORATION OF CONNECTICUT.

WIRE CHAIN.

1,305,673.

Specification of Letters Patent. Patented June 3, 1919.

Application filed July 15, 1916, Serial No. 109,553. Renewed October 24, 1918. Serial No. 259,598.

To all whom it may concern:

Be it known that I, FRIEND W. SMITH, Jr., a citizen of the United States, residing at Bridgeport, in the county of Fairfield and 5 State of Connecticut, have invented a certain new and useful Improvement in Wire Chains, of which the following is a specification.

This invention pertains to wire chains and 10 has for its main object the production of a chain wherein the ends of the wire extending from the bow or loop of the link are interlocked in the formation of the eye in such manner as to prevent spreading or 15 collapse of the loop under stress. Furthermore, the eye is strong and there are no projecting ends which render the chain rough, so that it will not gather lint and waste. Again, the construction is such that 20 the chain may be readily employed as a sprocket-chain, a point of manifest advantage.

While being flexible, in that there is no pinching or binding of the interconnected 25 loops and eyes, the loops will maintain their shape under ordinary strains; that is to say, they will not spread nor collapse, such action to a great extent being prevented by the crossing over of the loop or bow ends in the 30 formation of the eyes, as will be hereinafter set forth.

The invention is susceptible of various 35 embodiments and several of such are illustrated in the drawings, wherein:

Figure 1 is a face view of two interconnected links of the preferred form of the invention;

Fig. 2 a side elevation of the same;

Fig. 3 a perspective view;

Fig. 4 a like view of a link, with one of the eye sections broken away;

Fig. 5 a face view of a modified form of link;

Figs. 6 and 7 side and perspective views 45 thereof;

Figs. 8 and 9, 10 and 11, 12 and 13 and 14 and 15 face and side elevations, respectively, of four other modifications.

Referring first to Figs. 1 to 4, each link 50 is formed from a single piece of wire bent to form and comprises a bow or loop, shown as elongated in form, having an end or curved portion 1 and side strands or elements 2 and 3. In forming up the link 55 the side strands are each carried inwardly

and cross each other, each being slightly bowed or offset, as at 4, where they contact in crossing. Each strand end is then bent laterally and upwardly, and in opposite directions, thence downwardly to a point below that where the strands cross at the upper end of the loop, and is then carried inwardly through and in contact with the cross-over members of the loop body, and finally turned in beneath the first lateral bend in the eye. 60

Stated in another way, the eye of the link may be said to be formed by turning each strand end outwardly, as at 5, above the bowed crossing portions 4, said outward portion 5 (and the remainder of the eye as 65 well) lying in a plane which stands at right angles to a plane passing longitudinally through the elements 2 and 3; from 5 the strand passes into a semicircular portion 6, the opposite element 7 whereof extends 70 downwardly to a point below the cross-over sections 4, being carried beneath the same, as at 8, and thence upwardly inside and in contact with the adjacent strand, the in-curved end 9 lying beneath and close to the 75 out-turned or eye section 5. By this formation each end 9 of the strand is protected or covered. At the same time a twin eye is formed at one end of the loop, the two strands which form the eye lying side by 80 side, as do also the lower and what may be termed the anchoring or hook ends of the eyes, composed of the lower portion of element 7, the curved section 8 and the in-turned end 9. It is also to be noted that 85

the eyes proper and the anchoring sections of the eyes are bent or formed in opposite directions to each other, and that the anchoring sections both pass through the upper end of the loop beneath the cross-over sections 4. Thus, the loop end adjacent the eye is firmly held in place and against spread or collapse under strain, and the formation is such as to provide for covering or housing of the end of the inturned portion 9. 90

The combined eye and anchoring element 95 may be said to have the general outline of a figure 9, see Fig. 2, the upper portion whereof forms the eye proper and the lower tail portion the anchoring element.

In the construction shown in Figs. 5 to 7 inclusive, the construction is the same as that above set forth, except for the manner in which the ends of the strands are curled or anchored.

- In this instance, instead of extending the eye strand downwardly, as at 7, said down-going side is carried over the crossing strands 4, as at 10, and then curled inwardly through 5 the bow and around the strand. In other words, the anchoring ends of the eyes are merely curled around the upper end elements of the bow in directions reverse to that shown in the form first described.
- 10 With the form illustrated in Figs. 8 and 9 the side strands cross each other as before, and the eyes are formed by carrying the strands upwardly, as at 11, and also inwardly toward each other at the upper portion 12 of the eye, the strands being then carried downwardly between the lower portion of sections 11 and over the cross-over portion 4 of the loop, thence through the loop below said portion, as denoted by 13, and the ends 14 turned inwardly beneath the overlying portions of the eye.
- 15
- 20

The construction illustrated in Figs. 10 and 11 is a reversal of that shown in Figs. 8 and 9. The strands cross as at 4, but instead of carrying the anchoring portions or elements of the eyes down between the elements thereof, said portions, denoted by 15, are carried over the crossing portions 4 and thence pass inwardly and upwardly, 25 the extreme ends 16 extending beneath and being covered by the eye proper.

In Figs. 12 and 13 the upper portions of the side strands of the loop are crossed, as at 4, and are deflected to one side, as at 17, 30 both in the same general direction and to the same side of the loop, then curved upwardly, over and downwardly forming eyes, the ends 18 being carried through the loop beneath cross-over 4, thence upwardly and 35 between the lower portion of the curved and deflected portions 17.

The construction illustrated in Figs. 14 and 15 is similar to that last described. The side strands, as in all the other forms, cross 40 over at the upper end of the loop, as at 4. They are then deflected laterally of the loop, as at 19, extend upwardly over and downwardly, forming the eye and have their 45 lower ends (which pass beneath the crossed-over members) coiled or twisted around said members, as at 20.

Under all the forms, strain applied to the chain has a tendency to force or draw the component elements of the eyes together, a 50 point of manifest advantage. Furthermore, as above indicated, the bows or loops of the chain limbs cannot be spread, nor will they elongate under normal strain, this by reason of the fact that the ends of the strands which 55 form the anchoring elements of the twin eye pass through the bow or loop and bind or tie the cross-over elements of the bow or loop end together.

It is also to be noted that under all the 60 constructions the terminals or ends of the

wire pass through and clear of the loop and the ends extend toward the eye, and in all the constructions, with the possible exception of the last modification, the ends are covered by the overlying eye portions.

70

Having thus described my invention, what I claim is:

1. A wire chain, each link of which consists of a bow portion and two eye portions, the wire from which said link is formed 75 crossing intermediate said bow and eye portions, with the terminal of each eye anchored or interlocked to the cross-over portion of the strand which extends from the opposite side of the bow, whereby the eyes and bow 80 are anchored to each other.

2. A chain, each link of which consists of a bow portion and eye portions that are disposed in planes at right angles to each other, the side wires of the bow terminating 85 in said eyes, and each side wire being on a side of the link opposite to that on which its corresponding eye portion is located.

3. A chain, each link of which consists of a bow portion and eye portions formed from 90 a single piece of wire, the strands of the sides of the bows crossing each other, and the eyes being formed as extensions of said strands, the ends of the wire passing through the bow in contact with the cross-over portions and then being bent and housed at the bases of the eyes in parallelism and substantially in contact.

4. A chain, each link of which consists of a bow portion and eye portions formed from 100 a single piece of wire, the bow and eye portions being disposed in planes at right angles to each other, the side strands of the bow crossing each other at one end of the bow, then being curved upwardly and 105 downwardly each in a direction the reverse of the other, with the lower end of each turned inwardly through the bow in parallelism, substantially in contact with each other, and also in contact with the crossed wires thereof, the terminals lying below and being covered by the adjacent upwardly-extending portions of the eye.

5. A chain link formed from a single piece of wire bent to form, and comprising a bow 115 portion and two eye portions, said eye portions lying side by side and each having the general outline of a figure 9, the upper portion whereof forms the eye proper and the lower portion an anchoring element embracing that strand of the loop which passes therethrough and extends to the other eye portion.

6. A chain link formed from a single piece of wire bent to form and comprising a bow portion and two twin eye portions, the eyes being disposed in planes which are at right angles to the plane of the bow, the eyes lying side by side and in reverse position and each having the general outline or contour of a 120 125 130

figure 9, the upper portion whereof forms the eye proper and the lower portion an anchoring element embracing that strand of the loop which passes therethrough and extends to the other eye portion.

7. A chain link formed from a single piece of wire and comprising a bow portion and two eye portions, the side strands of the

bow crossing each other and being engaged by and anchored to the inturned ends of 10 the eyes, which pass through the bow portion and lie in contact with each other within the loop.

In testimony whereof I have signed my name to this specification.

FRIEND W. SMITH, JR.
